UNITED STATES PATENT OFFICE.

HENRY WOLF EISENHART, OF YORK, PENNSYLVANIA, ASSIGNOR TO A. B. FARQUHAR COMPANY, LIMITED, OF YORK, PENNSYLVANIA.

FEED MECHANISM FOR FERTILIZER-DISTRIBUTERS.

No. 801,139.

Specification of Letters Patent.

Patented Oct. 3, 1905.

Application filed July 26, 1905. Serial No. 271,344.

To all whom it may concern:

Be it known that I, HENRY WOLF EISENHART, a citizen of the United States, residing at York, county of York, and State of Pennsylvania, have invented certain new and useful Improvements in Feed Mechanism for Fertilizer-Distributors, of which the following is a specification.

My invention is primarily for use on force-
10 feeds of the kind set forth in Letters Patent
No. 364,969, of June 14, 1887, and No. 296,239,
of April 1, 1884, although its use is not lim-
ited thereto.

It consists in certain improvements designed
15 to facilitate the taking apart and cleaning of
the moving parts of the feed, to lessen the
friction and render the movements of the parts
smooth and easy, and to prevent the sifting
20 of the pulverized fertilizing material through
the joint between the toothed feed-wheel and
the bed-plate against which it runs.

The improvements will first be described by
reference to the accompanying drawings,
forming part of this specification, and will
25 then be more particularly pointed out in the
claims.

In the drawings, Figure 1 is a plan of so
much of a fertilizer-distributer-feed mechanism
30 as necessary to an understanding of my
improvements. Fig. 2 is a vertical section of
the same on line 2 2, Fig. 1. Fig. 3 is a bottom
plan of the bed-plate. Figs. 4 and 5 are bottom
35 views of the two parts of the crown-feed
wheel detached from one another.

The feed mechanism shown in the drawings
is in general plan what is known as the "Spangler"
40 feed, the subject of the two Spangler
patents, Nos. 296,239 and 364,969, hereinbefore
referred to.

40 A is the bed-plate, provided with the usual
discharge-throat a.

B is the feed-wheel, consisting of the toothed
disk b, the circular base-plate c, and the annular
45 circular wall d, which rises from the
rim and affords a support for the toothed disk
b, provided on its under face with an annular
flange b', Figs. 1 and 5, which fits into the
50 mouth of the pot which it covers, these
parts being held together by a central bolt e,
which passes up through the wheel from
below and has on its projecting upper end a but-
terfly thumb-nut n. Upon the under face of

the base-plate is cast the cogged crown-wheel 55
m, through the hub m' of which the bolt e
passes. This hub fits in a central socket in
the spider s, which is on the under side of the
bed-plate A and is cast in one therewith. The
spider has retaining loops or bearings for the 60
beveled driving-pinion p, which meshes with
the crown-wheel m and is driven by the power-
shaft r.

C is the clearer-cap, which has the function
of the part lettered m in Patent No. 296,239 65
and f in Patent No. 364,969.

D is the pivoted combined scraper and gate,
corresponding to the device g of Patent No.
364,969.

The parts thus far described are actuated 70
and have substantially the same mode of op-
eration as in the well-known Spangler feed,
above mentioned, and they therefore require
no further description here.

I proceed now to point out the improve- 75
ments which constitute the present invention.

The Spangler feed and all feeds made and
operating on that plan are open to the objec-
tion that they are liable to clog up the phos- 80
phate when it gets wet, and the drill lies 85
awhile unused, baking fast to the parts, so as
to render it necessary to take apart and clean
the mechanism. This when the feed-wheel
was arranged as in the patents referred to,
with the base-plate c located below the bed- 90
plate A and pressed up and bearing against
the under face of the same, was a very trouble-
some undertaking, involving, among other
things, the removal of the driving-shaft r and
also the detaching and removal of the spider 95
s. Under the present improvement all this
difficulty is obviated. The base c of the feed-
wheel, as will be seen by inspecting the draw-
ings, is located above instead of below the
bed-plate A and takes its bearing upon the 100
upper instead of the lower face of that plate,
and the bolt e, by which the parts of the feed-
wheel are held together and the wheel as a
whole is secured to the spider s and bed-
plate A, passes centrally up from below 105
through the spider and the hub of the feed-
wheel and has on its screw-threaded end,
which projects above the face of the toothed
feed-disk b, a butterfly thumb-nut n, by screw-
ing down which the parts will be drawn 110
tightly together and the wheel as a whole will
be held securely in place in or on its bearings.
On the other hand, whenever it becomes nec-

essary to take apart and clean the feed all that is needed is to remove the nut *n* (and of course the cap *C*, if that be used) and the feed-wheel can at once be lifted out with entire ease and without disturbing any of the other parts of the mechanism, the opening in the bed-plate in which the feed-wheel is located being large enough to permit the passage through it of the crown-wheel *m* on the under face of the base *c*. Inasmuch as under this arrangement the spider *s* need not be disturbed, I am enabled to cast it in one with the bed-plate and to obtain the advantages growing out of that change. Moreover, to reduce friction as far as possible and to render the running of the feed-wheel smooth and easy and also to prevent the fertilizer in the box from sifting through the joint between the feed-wheel and the bed-plate, and thus escaping from the machine, I form around the opening in the bed-plate *A*, through which the feed-wheel passes, an annular circular curb or vertical flange *r*, upon which the under face of the rim of the base-plate *c* of the feed-wheel bears. The top of this curb and the under face of the rim, which runs on said curb, are both of them trued and dressed off to fit flat together closely, so that while they permit of smooth running with minimum friction they at the same time make a fit with one another so tight as to prevent any escape of the fertilizer, thus removing a serious objection to feed mechanisms of this general kind.

Having now described my improvements and the manner in which the same are or may be carried into effect, I state in conclusion that I do not limit myself strictly to the structural details hereinbefore set forth in illustration of the invention, since manifestly the same can be varied considerably without departure from the spirit of the invention; but,

What I claim herein as new, and desire to secure by Letters Patent, is as follows:

1. In a feed mechanism for fertilizer-distributors the combination of a force-feed wheel having a circular base with a crown-wheel on its under face, a toothed feed-disk and an intervening circular wall, as described, a bed-plate having an opening in which the feed-wheel is located with its base above the bed-plate and taking its bearing against the upper face of that plate, and means for supporting and holding the feed-wheel in place in the bed-plate, substantially as hereinbefore set forth. 45
2. In a feed mechanism for fertilizer-distributors, the combination of a force-feed wheel having a circular base with a crown-wheel on its under face, a toothed feed-disk and an intervening wall as described, a bed-plate and a spider in which the feed-wheel is centrally supported, with its base located above the bed-plate and bearing against the upper face of that plate, a central bolt passing 60 from below up through the spider and the feed-wheel, and a retaining-nut on the end of the bolt which projects above the feed-wheel, substantially as hereinbefore set forth. 65
3. In combination, the bed-plate having an opening for the feed-wheel of sufficient diameter to permit the passage therethrough of the crown-wheel on the feed-wheel, and an annular curb or vertical flange surrounding said opening, the feed-wheel having a base provided with a crown-wheel on its under face and located above and resting by its rim in said curb, and means for holding the feed-wheel in position and drawing it down to a close bearing on the curb, substantially as and 70 for the purposes hereinbefore set forth. 75

In testimony whereof I affix my signature in presence of two witnesses.

HENRY WOLF EISENHART.
